To all whom it may concern:

Be it known that I, JONATHAN CRABTREE, of Philadelphia, in the county of Philadelphia, State of Pennsylvania, have originated a new Design for a Carpet-Pattern; and I do hereby declare that the accompanying drawing, and following explanation thereof, form a full, clear, and exact description of the said design.

In the drawing, the complete pattern is shown, the face of the carpet presenting a repetition of that which appears, and the pattern consisting of figures A A A A A, of the arrangement and character represented.

Each of these figures A is surrounded by foliated ornaments a, composed of flowers, leaves, and stems, as clearly shown in the drawing.

The space between the figures A is occupied by an-

gular and curved lines, so arranged in respect to each other that they shall form the square ornaments b and circular or spiral ornaments c.

Irrespective of the colors employed,

I claim the design for a carpet-pattern, substantially as described, and as represented in and by the accompanying drawing.

In testimony whereof, I have signed my name to this specification, in the presence of two subscribing witnesses.
